UNITED STATES PATENT OFFICE.

FRANK P. WILLIAMS, OF DETROIT, MICHIGAN.

SHEET-METAL BED.

1,414,765.

Specification of Letters Patent.

Patented May 2, 1922.

Application filed April 27, 1921. Serial No. 464,920.

To all whom it may concern:

Be it known that I, FRANK P. WILLIAMS, a citizen of the United States, residing at Detroit, in the county of Wayne and State of Michigan, have invented certain new and useful Improvements in Sheet-Metal Beds, of which the following is a specification.

This invention relates to sheet metal beds, and has for its object a bed constructed almost wholly of sheet metal and which locks together with simple sliding joints.

In the drawings,—

Fig. 1 is a side elevation of a bed.

Fig. 2 is a plan view of the same with a part of the header strip broken away.

Fig. 3 is a vertical longitudinal section on the line 3—3 of Fig. 2.

Fig. 4 is a vertical cross section on the line 4—4 of Fig. 2.

Fig. 5 is a section on the line 5—5 of Fig. 4.

Fig. 6 is a section on the line 6—6 of Fig. 4.

Fig. 7 is an enlarged section on the line 25 7—7 of Fig. 2, showing how the clip 2 fastens the header strip to the head or foot-board.

The head board of the bed is made up of two head plates *a* and *b* provided with lock-seam folds at each outside edge in which locks the folded-over edges of the post strips *c*, as is shown in Fig. 5. These head plates are turned over at the bottom, as shown in Fig. 3, to form right-angular doubled back folds, the fold *d* closing the opening that would otherwise be in the bottom of the head board, and the fold *e* forming a supporting strip for the front ends of the side rails.

The side rails are designated *f* and are formed of a single strip of metal bent to form a closed channel with the upwardly-projecting fold or flange *g* and downwardly-projecting fold or flange *h*, in the latter of which the seam is made simply by folding one edge of the metal over the other. The ends of the side rails are provided with turned-out flanges *i* adapted to be slid in between the lock-seam fold of the post strip and the front plate of the head board. The lower wall of the channel of the side rail *f* will rest on the top of the folded-over strip *e*, thereby locating the side rails at the proper height. However, to prevent the load of the springs, mattress and occupants carrying the side rails down by bending over the folded-over strip *e*, the post strips are perforated, as is also

the head plate and the end flange *i* of the rail, so that a bolt or other securing member *j* may be passed therethrough as shown in Fig. 5, to prevent the load carrying the side rails down.

One or more cross members *k* may be bridged across from rail to rail and have their projecting ends rest upon the upper wall of the channel of the side rails, as is shown in Fig. 4. These form a support for the springs. These cross members are constructed very similarly to the side rails, being a closed channel with outwardly-projecting flanges or folds and with flat end extensions that permit the cross member to rest upon the side rails.

It will be seen that the front and rear plates *a* and *b* of the head board have their upper edges turned over into box-like folds 75 *l*. This is adapted to receive the header strip *m* which has downwardly-turned flanges *n* that are adapted to fit over these box-like folds and make a strong reinforcement for the head board at the top and at the same time give an ornamental appearance. These header strips also hold in place the vertical reinforcing channels *o* which comprise channel strips of metal folded into channel form with turned-in edges *p* at the opening of the channel and with a turned-out lip *q* at the top which fits in between the box-like fold *l* and the header strip *m* so as to securely anchor the reinforcing channels *o* in place. There are, preferably, two of these reinforcing channels used in the construction shown. This prevents the head plates from buckling in and reinforces the entire head construction.

The post strip *c* continues down to the 95 floor and has lock-seamed thereto below the head plates a channel fillet strip *r* (see Fig. 6), which has turned-out folds to engage in the lock-seam folds of the post strip. This provides a strong, durable post.

The construction of the foot-board is the same as the head-board in general. However, the foot-board is not as high and a modified form of construction at the bottom of the foot-board is shown. In place of the 105 folded over strips *d* and *e* at the bottom of the foot-board, folded lips *s* and *t* are turned in and a single channel strip *u* is forced down into these turned-in lips to form the base of the foot-board. The side rails are 110 arranged in the foot-board the same way as in the head and the post strips lock into the

5 folds of the foot-board plates in the same way and have the same character of box-like folds *x* at the top of the foot-board plate that receives the header strip *w* of the foot-board with the turned-over edges *y*. Both 10 the head and foot board header strips are held in place by the locking strip 2 shown in Fig. 7. These can be folded into the lock-seam fold of the header strip and when the 15 header strip can slip over the box-like fold of the head board or foot board the strip may be folded into the position shown in the dotted lines, Fig. 7.

15 From the above description it will be apparent that this bed is made, outside of the bolts for anchoring the side rails in place, entirely of sheet metal folded into lock-seams which can slide together and be held in place simply by friction. This forms a 20 knock-down bed which can be made by simple sheet metal stampings in large production, shipped in a knock-down condition and assembled together by the retailer or the user. This will effect a very unusual 25 saving in bed constructions of this type. With the many improvements that have come into vogue in the way of painting sheet metal in imitation of the natural woods, this bed will make a very acceptable substitute 30 for the more expensive wooden bed.

What I claim is:

1. In sheet metal furniture, a member for use as a head, foot-board or similar relation, comprising a pair of parallel plates 35 with turned-out lock-seam folds turned back to parallel the plates and each other and a pair of post strips comprising channels having turned-in lock-seam folds paralleling the side walls of the channel adapted to engage 40 the lock-seam folds of the plates to lock the plates together and form the composite member.

2. In sheet metal furniture, a member for use as a head, foot-board or similar relation, 45 comprising a pair of parallel plates of sheet metal with lock-seam folds at the ends and channel strips with lock-seam folds locking into the lock-seam folds of the plates to form the posts and hold the plates together to 50 form a composite member.

3. In sheet metal furniture, a member for use as a head, foot-board or similar relation, comprising a pair of sheet metal plates, 55 channel strips with lock-seam folds detachably locking into the lock-seam folds of the side edges of the sheet metal plates to form the posts and hold the plates together to constitute the composite member, said channels with the lock-seam folds continuing below 60 the plates to form the lower run of the posts, and fillet channels locking into the said folds of the lower run of the posts to reinforce the same.

4. In sheet metal furniture, a member for 65 use as a head, foot-board or similar relation, comprising a pair of plates, post strips detachably interlocking with the side edges of the plates to form the posts and space the plates, and reinforcing strips engaging between the plates having at their top a 70 turned-over lip for anchoring the reinforcing strips at the top of the plates.

5. In sheet metal furniture, a member for use as a head, foot-board or similar relation, having in combination, a pair of plates 75 with side edge portions, post strips detachably engageable with the side edge portions of the plates to form the posts and hold the sheet metal plates apart, said sheet metal plates being provided with upper turned-over edges, and a flanged header strip adapted to slide over the upper turned-over edges to complete the top of the member.

6. In sheet metal furniture, a member for use as a head, foot-board or similar relation, 85 having in combination, a pair of plates with side edge portions, means for uniting the side edge portions, said plates having turned-over box-like channels or folds at the top, and a header strip having turned-down 90 flanges adapted to lock over the box-like folds to complete the top of the member.

7. In sheet metal furniture, a member for use as a head, foot-board or similar relation, having in combination, a pair of plates 95 united at their side edges and having box-like folds turned over at the top, reinforcing channels engaging between the plates between the side edges thereof and having turned-over lips at the top, and a header strip adapted to engage over the box-like 100 folds at the top and over the turned-over lips of the channel reinforcing strips to anchor the same in place.

8. In a sheet metal bed, the combination 105 of a member for use as a foot or head-board, including a plate and a post strip which folds over the turned-out side edge of the plate, and a side rail, comprising a channel-like strip having turned-out end flanges 110 which can be slid in between the folded-over post strip and the plate to anchor the end of the side rail to the said member.

9. In a sheet metal bed, a member for use as a head or foot-board including a plate 115 having a turned-out lock-seam fold and a post strip having a turned-in lock-seam fold that locks with the lock-seam fold of the plate, and a side rail, comprising a closed channel strip having a turned-out 120 end flange adapted to be slid in between the said lock-seam folds to anchor the side rail to the said member.

10. In sheet metal furniture, a side rail comprising a single strip of metal folded 125 to form a shallow channel with right-angularly extending folds or flanges extending outwardly at the mouth of the channel and united by a web of the metal that extends over the mouth of the channel, the said 130

flanges being vertically disposed when the rail is in place and located on the outside of the rail, thereby serving as end abutments for the cross rails and the upper side of the 5 channel portion of the rail serving as a seat for the cross rails.

11. In a sheet metal bed, the combination of head and foot boards, side rails anchored by the head and foot boards and 10 comprising each a single strip of sheet metal formed into a closed channel having at the outside of the rail upwardly and downwardly extending flanges or folds, and cross members comprising each a sheet metal 15 closed channel having flat end extensions which can rest on the upper side walls of the channels of the rails while the channel portion of the cross member extends down

below the upper side walls of the channels in the side rails. 20

12. In a sheet metal bed, a side rail comprising a hollow member of rectangular section which when in place in the bed is relatively shallow in horizontal cross section and relatively wide in vertical cross section 25 with the outside wall of the rail extending upwardly and then downwardly beyond the top wall of the rectangular section to form an upwardly-extending flange which can act as an end abutment for the cross rails while 30 the top wall of the section acts as a seat for the cross rail.

In testimony whereof I affix my signature.

FRANK P. WILLIAMS.
